UNITED STATES PATENT OFFICE.

VERDIE C. RUFTY, OF STONY POINT, NORTH CAROLINA, ASSIGNOR OF ONE-HALF TO
L. O. MOOSE AND J. O. RUFTY, BOTH OF STONY POINT, NORTH CAROLINA.

WINDOW-SHADE BRACKET.

Application filed October 19, 1926. Serial No. 142,678.

The invention relates to a shade fixture and more especially to the class of curtain shade operating means.

The primary object of the invention is the provision of a device of this character, wherein the curtain or shade roller is totally devoid of a spring or other winding medium, yet the same can be rotated for the adjustment of the curtain or shade and automatically locked or held fast in its adjusted position, the shade roller being manually operable, so that the curtain or shade can be conveniently adjusted, either for the extension of the same, or the retracting thereof, whereby the shade can be positioned to meet the fancy of the user when supported at a window.

Another object of the invention is the provision of a device of this character, wherein the holding of the shade roller against rotation is effected in a novel manner and wherein a single operating cord is employed, either to raise or lower the shade or curtain for the winding of the same upon or the unwinding of the same from such roller, the support for the roller being of novel form.

A further object of the invention is the provision of a device of this character, wherein the shade or curtain roller will be automatically held fast immediately following adjustment thereof to raise or lower the curtain or shade at a window or other opening, the said roller or shade being operated from a side cord, manually actuated and guided in a unique manner.

A still further object of the invention is the provision of a device of this character, which is extremely simple in its construction, neat and attractive in its appearance when applied, thoroughly reliable and efficacious in its operation and purpose, strong, durable, and inexpensive to manufacture and install.

With these and other objects in view, the invention consists in the features of construction, combination and arrangement of parts, as will be hereinafter fully described, in detail, illustrated in the accompanying drawing showing the preferred embodiment of the invention and pointed out in the claims hereunto appended.

In the accompanying drawing:—

Figure 1 is a fragmentary elevation of a window casement or frame, showing the shade or curtain mounted thereon, with the

device constructed in accordance with the invention applied.

Figure 2 is an edge end elevation.

Figure 3 is a detailed sectional view on the line 3—3 of Figure 1 looking in the direction of the arrows.

Figure 4 is a perspective view in detail showing the other bracket for the window shade.

Similar reference characters indicate corresponding parts throughout the several views in the drawing.

Referring to the drawing in detail, A designates generally a window casement or frame which is of the conventional form and B the curtain shade, which also is of conventional form adapted to be wound upon and unwound from a roller C, which has the usual internal spring omitted for effecting the automatic winding and unwinding of the curtain shade of the present day type.

Projecting from opposite ends of the roller C are pintles 5 and 6, mounted to rotate in the circular opening 7 formed in the bracket 8 at one end of the roller and the vertically disposed slots 9 in the bracket 10 at the opposite end of the roller. These brackets 8 and 10, respectively, are fastened to the window casement or frame A in any desirable manner, preferably by the use of screws 11 and such brackets as usual are located at the head of said window casement or frame.

In the mounting of the roller C a suitable space is provided between the end of the roller adjacent to the bracket 8, the pintle 5 being lengthened to bridge this space, which is occupied by a grooved pulley 12 carried by said pintle and made fast to the roller C at the end adjacent thereto. Within the groove 13 in the pulley 12, which groove is of the conformation as shown in Figure 1 of the drawing there is reversely coiled about said pulley as at 14 an endless cord 15, which latter is also trained about a grooved guide pulley 16 journaled in hanger 17 fixed to the window casement or frame A contiguous to the sill or base thereof. This endless cord 15 is manually operated and the reverse coils 14 thereof embracing the pulley 12 will frictionally cooperate with the latter to effect a positive rotation of said roller C to effect the raising and lowering of the curtain shade B as will be clearly apparent. The journal 18 of the guide pulley 16 is removably fitted

in the hanger 17 through the medium of a wing nut 19 and said journal engages in an elongated slot 20 formed in each side of the hanger 17, so that the guide roller 16 can be varied in its adjustment to increase or decrease the tension of the endless cord 15 in its cooperative working with the pulley 12 and such journal 18 is locked in its adjusted position or held fast through the medium of the wing nut 19 when worked home against one side wall of said hanger 17 as will be clearly apparent.

Opening into the circular opening 7 in the bracket 8 is an upwardly directed slot 21 which is arranged tangentially to the periphery of the opening 7 and is adapted to receive therein the flattened portion 22 of the pintle 5, when the latter is moved automatically in an upward direction in a manner presently described and the said roller C becomes passive after the adjustment of the curtain shade B.

Formed on the bracket 8 and extending upwardly and outwardly in a crane or extension, or ear 23 with the free end of which is loosely connected a coiled retractile spring 24 having its other end formed with a loop or eye 25 loosely embracing the pintle contiguous to the head 26 at the extremity thereof, the latter being designed to retain the loop or eye 25 upon the pintle, which loop or eye 25 is positioned between the head 26 in the bracket 8 in which the head pintle 5 is engaged. This spring 24 at all times tends to draw the pintle 5 upwardly from the circular opening 7 into the tangentially disposed slot 21, so as to lock the roller C against rotation and thereby retain the shade B in its raised or lowered adjusted position.

When it is desired to adjust the shade B the operator merely grasps the cord 15 at one of the stretches thereof and pulls slightly upon the same which causes the pintle 5 to become lowered out of the slot 21 into the circular opening 7 and by manipulating the cord the roller C can be turned for either winding of the shade B

upon the roller or its unwinding therefrom to an adjusted position, raised or lowered relative to the window casement or frame A. 50 When the cord 15 is released of tension, the spring 24 becomes active upon the pintle 5 drawing the same from the circular opening 7 into the slot 21 in the bracket 8 and thereby locking the roller in passive position or 55 condition.

It is to be understood that the invention herein described is not limited in its use to a window shade, as the same may be adaptable for other purposes. It is also 60 understood that changes, variations and modifications may be made in the invention as come properly within the scope of the appended claims without departing from the spirit of the invention or sacrificing any 65 of its advantages.

From the foregoing it is thought that the construction and manner of operation of the device will be clearly understood and therefore a more extended explanation has 70 been omitted.

What is claimed is:

A shade fixture for the purpose referred to comprising a bracket formed at its inner side with an ear disposed at right angles 75 with respect thereto, said ear having a perforation for rotatably receiving a flat sided pintle and further formed with an upwardly directed straight sided locking slot disposed tangentially of and opening into said 80 perforation, an arm extending upwardly from the top of the bracket and formed at its upper end with an outturned portion, and a coiled spring having its upper end connected to said outturned portion and 85 adapted to have its lower end loosely engage, exteriorly of said ear, the pintle of the shade roller within the perforation to automatically shift the pintle from the perforation into the slot for normally retaining it there- 90 in under tensioned suspension.

In testimony whereof, I affix my signature hereto.

VERDIE C. RUFTY.
